UNITED STATES PATENT OFFICE.

LAWRENCE THEODORE THORN, OF LYNNVILLE, TENNESSEE.

STORE-CABINET.

1,261,652.

Specification of Letters Patent.

Patented Apr. 2, 1918.

Application filed February 5, 1917. Serial No. 146,742.

To all whom it may concern:

Be it known that I, LAWRENCE T. THORN, a citizen of the United States, residing at Lynnville, in the county of Giles and State 5 of Tennessee, have invented certain new and useful Improvements in Store-Cabinets; and I do declare the following to be a full, clear, and exact description of the invention, such as will enable others skilled in the art to 10 which it appertains to make and use the same.

This invention relates to new and useful improvements in store cabinets especially those adapted for use in grocery stores and 15 the primary object of the invention is to provide a cabinet provided with a plurality of bins arranged so that they are easily accessible and also the top portions of the same form a counter.

20 Another object of the invention is to provide a store cabinet of this character which is provided with a plurality of closely arranged bins forming a counter and capable of being moved from place to place.

25 A further object of the invention is to provide a store cabinet of this character which includes pairs of superposed bins having outlets in the bottom of the same and provided with means whereby the contents 30 of the upper bin may be removed therefrom without disturbing the contents of the lower bins.

A still further object of the invention is to 35 provide a device of this character in which the bins are separable, thereby making transportation comparatively easy.

Still another object of the invention is to 40 provide a store cabinet of this character provided with a plurality of bins, some of the bins being provided with means for receiving and displaying certain goods in packages, and also the goods being removable without removing the casing in which they are packed.

45 A further object of the invention is to provide a device of this character which is simple and durable in construction, inexpensive to manufacture, and one which will be very efficient and reliable in operation.

50 With these and numerous other objects in view, the invention consists of the novel features of construction, and the combination and arrangement of parts to be herein referred to and more particularly pointed 55 out in the specification and claims.

In the accompanying drawings:

Figure 1 is a top plan view of a complete set of bins in assembled form;

Fig. 2 is a vertical section on the line 2—2 of Fig. 1;

Fig. 3 is a vertical section taken on the line 3—3 of Fig. 1;

Fig. 4 is a horizontal section taken on the line 4—4 of Fig. 2; and,

Fig. 5 is a sectional view showing a modified form of the upper bin.

In describing my invention I shall refer to the drawings in which similar reference characters designate corresponding parts throughout the several views. The store 70 cabinet comprises a pair of rows of bins 1 and 2 which are positioned in substantially parallel spaced relation and which are connected at one end by three bins 3, 4 and 5, the middle bin 3 being disposed at right 75 angles to the rows and connected by angularly disposed bins 4 and 5. Each of these rows of side bins are made up of separable bins 1' and 2' which are held together by clamping screws 13. This arrangement of 80 bins forms a substantially U-shaped cabinet, and the top portions of the bins are connected and disposed in a single horizontal plane to form a counter 6 which extends therearound.

The side bins 1' and 2' have the forward portions of their tops provided with upwardly projecting partitioning members 7 which are connected by a front member 8 which extends along the front of the same. 90 This arrangement forms a plurality of goods receiving recesses 7' which are disposed above the bins and are provided with a top by the horizontally extending counter 6. The rear portions 9 of the tops of said bins 95 1' and 2' are open and hinged doors 10 are connected with the forward portions of the tops and adapted to form closures for the bins. The open tops form inlet openings for supplying the bins and also form means for 100 gaining access thereto to remove the contents as sold. These hinged doors 10 are inclined as clearly shown in Fig. 3 of the drawings. The recesses 7' and the bins 1' and 2' are provided in their outer walls with 105 enlarged openings 8' covered with glass 8" to display the contents thereof to the customers. The bins 1' and 2' are provided with depending flanges 21 which extend below the bottoms of said bins and are provided 110

on three sides with inwardly projecting portions or brackets 22 and on the fourth side with a hinged door 21", said brackets being adapted to support a pan 23 which is so positioned as to receive the contents of the bins upon removal of the closures 20 from the openings 19 in the bottom of said bins. Fig. 3 shows the fastening elements which are preferably clamping screws 13 and are used 10 to secure the bins together as more clearly shown in Fig. 4. Each bin is provided on its bottom with a bracket 25 and a roller 26 so that the entire cabinet is made portable and may be readily moved from place to 15 place and positioned as desired.

The front connecting bins 3, 4 and 5 are formed of pairs of upper and lower bins 11 and 12, the lower bins 12 having open tops and the bottoms of the upper bins forming 20 tops for the same.

For convenience, I will now refer to one of the pairs of three front bins 3, 4 and 5, it being understood that the structure of each is the same.

25 The upper bin 11 is disposed forwardly with respect to the lower bin 12 and the bottom of the same is detachably connected therewith by means of clamping screws 13 as clearly shown in Fig. 2 of the drawings. 30 These bins 11 and 12 are provided with display openings 14 in their outer walls and are covered with glass 15 to display the contents thereof to the customers.

The upper and lower bins 11 and 12 are 35 provided with inlet openings 16 in the inner walls of the same at their tops and are adapted to be closed by inclined doors 17 which are hingedly connected with the upper edges of the bins as clearly shown at 17'. The bins 40 11 and 12 are provided with outlet openings 18 and 19' respectively in their bottom walls and are provided with closures 20' normally positioned in said openings to hold the contents within the bins.

45 The lower bin 12 is provided with a downwardly projecting flange 21' on three sides as shown and a hinged door 21" on the fourth side, the three sides having inwardly projecting portions or brackets 22 adapted 50 to support a pan or other receptacle 23' thereon. The lower bin has a second inwardly projecting portion or bracket 24 near its upper end to receive the inner end of the pan or other receptacle 23' thereon when so 55 desired.

When it is desired to empty the contents of the lower bin for cleaning the same or replacing the same with fresh material, the closure 20' is removed and consequently the 60 contents will readily run therefrom and be received in the pan 23'. The removal of the closure 20' in the upper bin will allow the contents thereof to run into the lower bin 12 or if it is desired to simply clean the bin 11, 65 a pan 23' may be supported at its inner end

on the bracket 24 to receive said contents after which it is easily withdrawn, it being understood that the user supports the outer end of the pan by hand.

In Fig. 5 of the drawings I have illustrated a slightly modified form of the upper bins 11, the lower bins 12 being the same as those hereinbefore described.

Each bin 11' is provided in its outer wall with an opening 14' which is covered with 75 glass 15' to display the contents of the bin to the customers. The inner wall 27 of the bin 11' has therein an opening 28 adapted for alignment with the display opening 14' in the front wall of the same.

To form a closure for this opening 28, I have provided a door formed in two sections 29 and 31 connected by spring hinges 30, the entire door being connected to the lower edge of the inner wall by spring hinges 85 30'. The upper section 29 is provided with a catch 32 to lock the door in closed position.

The object of this type of door is to render the upper bins applicable for holding and displaying certain types of goods, as for 90 instance, dried fruits which are received in comparatively large boxes, it being only necessary to remove the tops and bottoms of the boxes and place them in the bins with one open side facing the display opening and 95 the other open side facing the door of the bin. This will display one side of the box through the display opening in the bin while owing to the fact that the door is formed, in two sections and the upper section 29 is 100 hingedly connected with the lower section 31, the material may be easily removed from the box by swinging the upper section outwardly. This makes the above mentioned type of goods easily accessible as well as displaying the same attractively. When placing a box of fruit in the bin, the two sections of the door may be swung down to permit the box to be easily set in the proper position, the opening of both door sections 110 being a great advantage when said box is nearly as large as the bin.

This type of store cabinet is especially adapted for use in grocery stores as the bins are applicable to hold the various goods that 115 are retailed. Owing to the U-shaped arrangement of the bins, all of the materials are easily accessible to the clerk, and furthermore, as each of the bins is provided with a display opening in its outer wall, the 120 contents of each of the bins is attractively displayed to the customer. Goods receiving recesses formed above the parallel rows of spaced bins are adapted to hold various articles such as boxes of crackers, etc., that 125 the grocer has a ready sale for and which should be placed so that they are easily accessible. Secured to the upper edges of the upper bins that connect the ends of the spaced rows of parallel bins is the counter 6 130

which also extends above the parallel bins and over the goods receiving recesses. This counter is adapted to receive thereon the various articles which are necessary in the 5 operation of the business.

From the foregoing description of the construction and operation of my new and improved store cabinet, the manner of applying the same to use and the operation thereof 10 will be readily understood, and it will be seen that I have provided a simple and efficient means for carrying out the objects of the invention.

I claim:—

- 15 1. A device of the class described comprising pairs of superposed bins with the bottom of each upper bin forming the top of the lower, said bins having display openings in the front faces thereof, the rear edges of said bins having inlet openings, doors hinged to the bins and adapted to cover said inlet openings, the bottom of each bin having an outlet, closures for said outlets, and a bracket adjacent the upper 20 edge of the lower bin to support a receptacle beneath the outlet of the upper bin, whereby the contents thereof may be removed 25 without disturbing the contents of the lower bin.
- 30 2. A device of the class described comprising pairs of superposed separate bins with the bottom of each upper bin forming the top of the lower, said upper bin extending forwardly from the lower bin and 35 secured to the upper edge of the same, the

top of said upper bin being adapted to form a counter, said bins having display openings in the front faces thereof, inclined doors hinged at the top edges of the bins and adapted to cover inlet openings in the 40 rear walls of the same, the bottom of each bin having an outlet, closures for said outlets, and a bracket secured to the inner surface of the front wall of the lower bin adjacent its upper edge to support the front 45 edge of a receptacle adapted to be disposed beneath the outlet of the upper bin for removal of its contents.

3. The combination of a lower bin open at its top and having a transverse strip extending across said top in parallel relation to the rear wall of the bin, a downwardly and rearwardly inclining door hinged to said strip and resting on the upper edge of the rear wall of the bin, a flange extending 50 forwardly from the upper edge of the front wall of said bin, an upper bin whose bottom rests at its rear edge on said strip, said bottom also resting on said flange, and bolts passing through said bottom and through 55 said strip and flange to secure the two bins together, the upper bin projecting forwardly beyond the lower bin.

In testimony whereof I have hereunto set my hand in the presence of two subscribing 60 witnesses.

LAWRENCE THEODORE THORN.
